UNITED STATES PATENT OFFICE.

OSKAR FISCHER, OF BERLIN-FRIEDENAU, GERMANY, ASSIGNOR TO N. V. MACHINA MAATSCHAPPIJ VOR HANDEL EN INDUSTRIE, OF AMSTERDAM, NETHERLANDS, A CORPORATION OF THE NETHERLANDS.

TABULATION MECHANISM OF TYPEWRITING MACHINES.

Original application filed January 25, 1924, Serial No. 688,399. Divided and this application filed April 10, 1925, Serial No. 22,061, and in Germany November 4, 1918.

My invention relates to improvements in the tabulation mechanism of typewriting machines, and the object of the improvements is to provide a tabulation mechanism which is simple in construction and handy in operation. With this object in view my invention consists in disposing the tabulation stops on a bar provided at the front side of the carriage. Therefore the said stops are readily accessible, and, further, I am enabled to provide very short tabulation key levers, which key levers extend from the rear part of the keyboard and through the front part of the frame into position for engagement with vertically shiftable rods adapted to be lifted by the key levers into position for engagement with the said tabulation stops.

For the purpose of explaining the invention an example embodying the same has been shown in the accompanying drawings in which the same reference characters have been used in all the views to indicate corresponding parts. In said drawings,

Fig. 1, is a sectional elevation showing the upper part of a typewriting machine.

Fig. 2, is a top plan view of Fig. 1 with the upper part of the paper carriage removed, and

Fig. 3, is a sectional elevation on a broken plane of section.

In describing the invention it will be assumed that my improved tabulation mechanism is embodied in a typewriting machine of the type shown and described in my original application for Patent Ser. No. 688,399, filed January 25th, 1924, now Patent 1,553,765, dated Sept 15, 1925, of which the present application is a division. But I wish it to be understood that my invention is not limited to the use of the tabulation mechanism in a machine of the type referred to in the said original application. In the present application I shall make reference to the tabulation mechanism and such parts of the machine as are necessary for getting a clear understanding of the said mechanism. For further information reference is made to the said original application.

In the example shown in the figures my improved typewriting machine comprises a frame 1 having a top plate 2. To the said top plate rails 3 and 4 are secured which pro-

vide a guide for a paper carriage 5, which carriage is provided with letter spacing mechanism constructed as follows: On the top plate 2 of the frame of the machine and at the rear thereof a bail consisting of a rail 6 of square cross-section and arms 7 is rockingly mounted in eyes 8 and 9 secured to the bottom side of the plate 2. On the rail 6 a slide 10 is movable or slidable and upon the slide a pawl 11 is pivoted at 12. One arm of the pawl carries a pin 13 engaging in a slot made in a plate 14 secured to a rail 15 of the paper carriage. The other arm of the pawl is normally in engagement with the lower one of a pair of racks 17 and 18. The upper rack 18 is secured to a rocking frame consisting of a transverse bar 19 rockingly mounted in eyes 20 and 21 secured to the plate 2, and arms 22, 23 and 24. The lower rack 17 is carried by the upper rack 18 and it is longitudinally slidable thereon a distance corresponding to the letter space. As shown a pair of screws 25, are passing through the slots 26 formed in the upper rack. A spring (not shown) tends to pull the lower rack to the right. The heads of the screws 25 are acted upon by springs 27 reducing the noise connected with the operation of the racks. The arm 23 is connected by a link 28 with a frame 29 rockingly mounted on trunnions 30. The frame 29 is adapted to be rocked by the armature of an electromagnet 31 for letter spacing after printing a letter, as has been described in my aforesaid original application for patent. When the armature is attracted by the electromagnet 31 the frame 29 and the link 28 are carried along, so that the pawl 11 temporarily releases the lower rack 17 and engages the upper rack. Thereupon the lower rack is pulled by its spring to the right. If thereafter the armature of the electromagnet 31 is released the racks 17 and 18 are lifted by a spring 50 (Fig. 1) so that the pawl 11 comes again into engagement with the lower rack, which is shifted by the carriage spring to the left together with the paper carriage.

The tabulation keys 32 are carried by levers 33 disposed with their inner or rear ends in positions for engagement with vertical bars 34. Said bars are acted upon by leaf

springs 35 tending to force the same downwardly and away from tabulation stops 36 placed on a rack 37 of the paper carriage. The bars 34 are adapted to rock a frame 38 mounted at 39, 40 and acting on a lever 41 mounted at 42. The free end 43, of the said lever is disposed above a head 44 adjustably mounted on an arm 45 secured to one of the arms of the rail 6. When depressing one of the tabulation keys the bar 34 controlled thereby is lifted into position for engagement with the tabulation stop 36 for arresting the paper carriage, and the rail 6 and the pawl 11 are retracted away from the racks 17, 18 so as to release the carriage, which is now pulled to the right. For reducing the impact of the carriage striking against the tabulation stop 36 a brake shoe 46 is provided which is forced by an arm 47 secured to the frame 38 against the bottom side of the rail 16 of the carriage.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

I claim:

1. In a type-writing machine the com-

bination of a frame, a paper carriage, a rack-and-pawl escapement device including a rack mounted on the frame a rail swingingly mounted on the frame a pawl slideable on the rail and engaged by the carriage, said bar in its range of swing carrying the pawl to and from a position of engagement with the rack, tabulation mechanism including a stop borne by the carriage and a bar borne by the frame and movable to and from stop-engaging position, and means for shifting said bar and swinging said rail simultaneously.

2. In a type-writing machine the combination of a frame, a paper carriage, a rail swingingly mounted on said frame, a rack-and-pawl escapement device arranged between frame and carriage, one of the components of said rack-and-pawl escapement device being movable with the carriage and slidably mounted on said rail and movable by the swinging of the rail to inactive position, tabulation mechanism including a stop borne by the carriage and a bar borne by the frame and movable to and from stop-engaging position said bar in its advance to stop-engaging position swinging said rail to the position of inaction of the escapement device.

In testimony whereof I hereunto affix my signature.

OSKAR FISCHER.
